(57) **CLAIM**

The ornamental design for a dehooker holder, as shown and described.

DESCRIPTION

FIG. 1 is a front, top, and right side perspective view of a dehooker holder showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front, top, and right side perspective view thereof showing an attachment to a vertical pole; and,

FIG. 9 is a front, top, and right side perspective view thereof showing an attachment to a vertical pole and a holding of a dehooker.

The broken lines showing a vertical pole in FIGS. 8 and 9 are for illustration purposes and form no part of the claimed design.

The broken lines showing a dehooker in FIG. 9 are for illustration purposes and form no part of the claimed design.

1 Claim, 6 Drawing Sheets
